UNITED STATES PATENT OFFICE

SANDERS C. SIMPSON, OF WOODCLIFF, NEW JERSEY

DESIGN FOR AN AQUARIUM STAND OR SIMILAR ARTICLE

Application filed January 14, 1930. Serial No. 34,127. Term of patent 3½ years.

To all whom it may concern:

Be it known that I, SANDERS C. SIMPSON, a citizen of the United States of America, residing at Woodcliff, Hudson County, New Jersey, have invented a new, original, and ornamental Design for an Aquarium Stand or Similar Article, of which the following is a specification, reference being had to the accompanying drawing, forming part hereof, in which the figure illustrates in perspective an aquarium stand having my new design.

I claim:

The ornamental design for an aquarium stand or similar article as shown.

Signed at New York city, New York, this 3rd day of January, 1930.

SANDERS C. SIMPSON.
